UNITED STATES PATENT OFFICE.

HENRY ORSENIGO, OF MOUNT VERNON, NEW YORK.

DESIGN FOR A RADIOCABINET.

Application filed March 26, 1925. Serial No. 12,894. Term of patent $3\frac{1}{2}$ years.

To all whom it may concern:

Be it known that I, HENRY ORSENIGO, a citizen of the United States, residing at Mount Vernon, county of Westchester, State of New York, have invented a new, original, and ornamental Design for Radiocabinets, of which the following is a specification, reference being had to the accompanying drawing, forming part thereof.

The figure is a perspective view of a radiocabinet showing my new design.

I claim:

The ornamental design for a radiocabinet, as shown.

HENRY ORSENIGO.
